UNITED STATES PATENT OFFICE.

LUTHER E. JEROME, OF NEW HAVEN, CONNECTICUT, ASSIGNOR TO THE
NEW HAVEN CLOCK COMPANY, OF SAME PLACE.

DESIGN FOR A CLOCK-CASE.

SPECIFICATION forming part of Design No. 16,900, dated September 14, 1886

Application filed July 3, 1886. Serial No. 207,146. Term of patent 7 years.

To all whom it may concern:

Be it known that I, LUTHER E. JEROME, residing at New Haven, in the county of New Haven and State of Connecticut, have invented and produced a new and original Design 5 for Clock-Cases; and I do declare the following to be a full, clear, and exact description of the same, reference being had to the accompanying drawing, which forms a part of this 10 specification.

The accompanying drawing is a view in perspective of a clock-case containing my newly-invented design.

The leading feature of my design consists in 15 a perforated and jeweled shell.

A is a square shell, provided with a pyramidal top, B, having a fluted or wavy edge, and furnished with a fluted cap, C, and a bail, D, the said shell and top being perforated, as 20 at E, and set with jewels F, as shown. The clock-dial G is mounted in one face of the shell, and, as herein shown, in that face thereof forming the door of the case.

What I claim is—

1. The design for a clock-case herein shown 25 and described, the same consisting of an upright body in the form of a shell, and having perforations and the ornamentation F, and said body also having a tapering top.
2. The design for a clock-case herein shown 30 and described, the same consisting of a body in the form of an upright flat-faced shell, and having a tapering top, such shell and upright being perforated, and having the ornamentation F.
3. The design for a clock-case herein shown 35 and described, the same consisting of a square perforated and jeweled shell having a pyramidal top.

In testimony whereof I have signed this 40 specification in the presence of two subscribing witnesses.

LUTHER E. JEROME.
